SAFETY DEVICE FOR GAS STOVES

Filed June 26, 1928

UNITED STATES PATENT OFFICE

BENJAMIN KAUPER, OF NEW YORK, N. Y.

SAFETY DEVICE FOR GAS STOVES

Application filed June 26, 1928. Serial No. 288,455.

The present invention relates to improvements in safety devices for gas stoves, primarily adapted to prevent the escape of the gas into a room or dwelling in the event the gas is accidentally, or otherwise, turned on. The invention contemplates the provision of a pilot-light in direct communication with a burner, or plurality of burners, whereby a flow of gas through an unlighted burner will be reduced to a flame to the end that the escape of gas into a room may be positively precluded.

The invention further includes the provision of a novel form of burner directly connected to a pilot light and associated with a deflector member for directing any escaping gas in close proximity to the flame of the pilot light in order that combustion may take place.

20 A further object is to provide novel means for controlling the flow of gas to the pilot light, whereby accidental turning on, or shutting off of the gas, is prevented.

Still another object of the invention is to provide novel means in the form of a deflector member, said member being arranged in substantially spaced concentric relation with the extension connecting a burner and the pilot light casing to permit the directive flow of the gas to the flame of the pilot light.

As will presently appear the invention is especially adapted to prevent death by asphyxiation in the event a lighted burner is extinguished by the wind, or the like, or a control valve is thoughtlessly or accidentally left opened or becomes opened.

With these objects in view, together with others which will appear as the description proceeds, the invention resides in the novel formation, combination, and arrangement of parts, all as will be described more fully hereinafter, illustrated in the drawings, and particularly pointed out in the claims.

In said drawings:

45 Figure 1 is a plan view of a gas stove embodying my invention.

Fig. 2 is a fragmentary sectional view taken substantially on the line 2—2 of Fig. 1, the deflector members being omitted.

50 Fig. 3 is a sectional view taken on the line

3—3 of Fig. 1 to depict the association of the pilot light casing and the deflector members.

Fig. 4 is a transverse sectional view of a deflector member as viewed on the line 4—4 of Fig. 3, certain other parts being excluded 55 for clarity.

Referring now in detail to the accompanying drawings, wherein like characters of reference denote similar parts throughout the several views, let 5 represent the top of a 60 gas stove of conventional design, which is provided with a plurality of burners 6, 7, 8 and 9 and a main gas supply pipe 10 extending from the usual mains. Each of said burners is provided with a conduit leading 65 from said supply pipe 10; burner 6 for instance having a conduit 11 through which the gas, under control, by means of valve 12, passes to said burner for subsequent ignition. Burner 7 is likewise provided with a 70 conduit 13 extending from the supply pipe 10, the gas flowage being controlled by valve 14. Conduits 15 and 16 are provided for burners 8 and 9 respectively, the gas being passed to the same by operating valves 17 75 and 18. The usual air intakes, as indicated at 19, are provided for each of said conduits.

While each of said burners is somewhat conventional in design, it will be observed that each is provided with an extension 20 80 leading to the pilot light casing 21, the latter being spherical in form and internally connected to said supply pipe 10 by means of tube 22, the flow of gas from the latter being controlled by a globe valve 23, as clearly 85 shown in Fig. 1. In the present example of the invention said pilot light casing 21 is positioned centrally of the burners and hence the extensions 20 are directed radially from said burners, it being of course understood 90 that other arrangements are contemplated according to the particular type of gas stove employed.

Upon inspection of Figs. 1 and 3 it will be observed that the ends of said extensions 20, 95 adjacent the pilot light casing 21, are each apertured, as indicated at 24, and that each of said extensions support a deflector member 25, the forward end of said member, adjacent the casing 21 being curved upwardly to de- 100

- fine a hood 26 disposed directly above the single apertures 24, or plurality of apertures, if desired. The tips of said hoods 26 are arranged in close proximity to the burner tip 27 of said pilot light casing 21, and hence the flow of gas from a burner may pass through aperture 24 and in view of the hoods 26 is directed adjacent the said burner tip 27, as will presently appear. 5
10. Reverting now to the valve arrangement previously described, it is manifest that the valve 23 must be manually operated to direct the gas to the pilot light or to stop the flow of gas thereto. Hence accidental opening or 15 closing of this valve is exceedingly remote, but a different situation presents itself with respect to the valves in the supply pipe 10, which require but a slight movement to effect their opening and closing.
20. However, with the pilot light ignited, it is obvious that the opening of any of the valves in said supply pipe 10, will cause the flow of gas to a selected burner or burners and thence through a particular extension 20 into the 25 pilot light, to be ignited at the tip 27. In view of the lips 28 and 29 associated with each of the deflector members 25, (see Fig. 3), the latter are each spaced from the end of said extensions 20 to provide a space clearly 30 shown in said figure. Ordinarily the pilot light is shielded from currents of air and always left burning so that by turning on the gas through either of the valves in the supply pipe 10, the gas flows to the burners, as 35 aforesaid, and finally escapes through apertures 24 over the burner tip 27, as indicated by the arrows, where the pilot flame ignites the same and also the gas escaping from the usual openings in the burners. The stove is 40 now ready for use.
45. From the foregoing it is obvious that the accidental opening of any of the valves in the supply pipe 10, causes the gas to flow as aforesaid, to and into the pilot light where it is ignited and this of course re-lights the burner in case of said accidental opening. Therefore, no raw gas can possibly find its 50 way into a room or home without coming into contact with the pilot light and becoming of itself ignited.
55. While the present is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.
60. I claim:
65. 1. In a gas stove, a pilot light casing having a tip, a burner including an integral extension connected to said pilot light casing and having an aperture adjacent said casing whereby gas is conducted from said burner to a point adjacent said casing and a deflector 70 member carried by said extension and having a hooded portion spaced from said aperture and adapted to direct the flow of gas to the tip of said pilot light casing. 75
2. In a gas stove, a pilot light casing having a tip, a burner including an integral extension connected to said pilot light casing and having an aperture adjacent said casing whereby gas is conducted from said burner to a point adjacent said casing and a deflector member carried by said extension and having a hooded portion positioned above and spaced from said aperture and having its outer edge spaced from the tip of said pilot light casing and adapted to direct the flow 80 of gas to said tip. 85
- In testimony whereof I affix my signature.
BENJAMIN KAUPER.
